UNITED STATES PATENT OFFICE.

ANDREW D. MORSE, OF HOPEDALE, MASSACHUSETTS, ASSIGNOR TO
SAWYER SPINDLE COMPANY, OF PORTLAND, MAINE.

BOBBIN-RETAINING MEANS FOR ROTATABLE SPINDLES.

SPECIFICATION forming part of Letters Patent No. 784,957, dated March 14, 1905.

Application filed February 1, 1905. Serial No. 243,608.

To all whom it may concern:

Be it known that I, ANDREW D. MORSE, a citizen of the United States, residing at Hopedale, county of Worcester, and State of Massachusetts, have invented an Improvement in Bobbin-Retaining Means for Rotatable Spindles, of which the following description, in connection with the accompanying drawings, is a specification, like characters on the drawings representing like parts.

This invention relates particularly to that type of bobbin-retaining means for rotatable spindles wherein centrifugally-acting clutching or retaining members are arranged to engage a yarn-receiver or bobbin when applied to the spindle and effect rotation thereof in unison with the spindle.

Ordinarily the clutching members are maintained in expanded or operative position when the spindle is running bare owing to centrifugal action, and the bobbin is pushed down over said members when it is put on the spindle, taking an appreciable time and force enough to temporarily contract the clutching members until they enter the chamber in the base or head of the bobbin.

In my present invention I have provided means to act automatically upon and retract the clutching members when the spindle is running bare, the application of the bobbin to the spindle by simply dropping it into place thereon acting through such means to release the clutching members, and thereby permit them to expand into driving engagement with the bobbin. When the bobbin is doffed, said means act automatically to retract the clutching members.

The various novel features of my invention will be fully described in the subjoined specification and particularly pointed out in the following claims.

Figure 1 is a part front elevation and vertical section of a portion of a rotatable spindle provided with bobbin-retaining means embodying one form of my invention, the spindle being supposed to be running bare. Fig. 2 is a similar view, but showing a bobbin in place to illustrate the means for releas-

ing the clutching members sufficiently to cooperate with and drive the bobbin. Fig. 3 is an inner side perspective view of one of the clutching members detached; and Fig. 4 is a transverse section on the line 4-4, Fig. 1, looking downward.

The rotatable spindle A, its whirl W, having an upturned neck w tightly secured to the spindle to rotate therewith and having an annularly-enlarged head w' to constitute a bobbin-rest, may be of well-known construction, and herein I have shown the head as provided with an annular groove or seat 1 in its top, forming a motion-limiting raceway.

A flat retaining-ring 2 is secured to the head and partly overhangs the seat, as shown, the head w being provided inside the seat with a tubular extension 3, which surrounds the spindle for some distance above the head, (see Figs. 1 and 2,) the upper end of the extension being cored out at 4 to form a seat for the lower end of a light spring 5, coiled around the spindle.

In the present embodiment of my invention a second motion-limiting raceway is mounted upon the spindle and movable relatively thereto, said raceway being shown as a collar 6, mounted to slide vertically on the spindle and resting on the upper end of the spring 5, a ring 7, secured to the spindle above the collar, limiting its upward movement.

The lower end of the collar 6 is shaped to present a circular upturned flange 8, having its upper face flared to constitute an annular cam 9, for a purpose to be described.

A plurality of centrifugally-acting bobbin-clutching members are arranged symmetrically around the spindle, one of such members being shown separately in Fig. 3 and comprising an elongated transversely concavo-convex body 10, having an outturned foot 11 and inturned and bent downward at its opposite or upper end at 12. (See Figs. 1, 2, and 3.)

The feet 11 of the several members are loosely inserted in the seat 1, and the flat retaining-ring 2 is then secured, permitting the

clutching members to rock radially on their feet within the seat 1, but preventing them from lifting out of position.

5 Radial pins 13, driven into the head across the seat 1, serve to separate the clutching members laterally and to effect their bodily rotation with the spindle.

The inturned or overhanging upper ends 12 of said clutching members enter loosely the 10 space between the flange 8 and the body of the collar 6, as clearly shown in Figs. 1 and 2, the cam 9 coöperating with the ends 12.

It will be seen from an inspection of the drawings that when the spring 5 lifts the collar 6, as in Fig. 1, the cam will act upon the inturned ends 12 to draw in or retract the upper ends of the clutching members toward the spindle, and if the latter is rotating the spring acts as described against the centrifugal action, which tends to expand or force outward the clutching members.

When a bobbin B, Fig. 2, is applied to a running spindle, the clutching members will therefore be retracted and will not offer any 25 resistance, so that the bobbin can be dropped into place. As soon, however, as the top of the bobbin-chamber b hits the rounded top 14 of the collar 6 the latter will be pushed downward, compressing the spring 5, (see Fig. 2,) 30 and as the cam 9 is lowered the upper ends 12 of the clutching members will be released sufficiently to permit them to expand instantly under centrifugal action and engage the walls of the chamber b to thereby rotate the bobbin 35 with the spindle.

The downward movement of the upper motion-limiting raceway is limited by the top of the extension 3, so that the upper ends of the clutching members cannot be wholly disengaged from the limiting or controlling action of the cam 9.

When the bobbin is doffed, the spring expands and raises the collar 6, thereby automatically retracting the clutching members 40 while the spindle is running bare.

My invention is not restricted to the precise construction and arrangement herein shown and described, for so far as I am aware it is broadly new in a centrifugally-acting 50 bobbin-clutching device to provide means to retract the clutching members when the spindle is running bare, the application of the bobbin acting through said means to release the clutching members and permit them to 55 expand and coöperate with the bobbin. Accordingly various changes or modifications may be made by those skilled in the art without departing from the spirit and scope of my invention.

60 Having fully described my invention, what I claim as new, and desire to secure by Letters Patent, is—

1. The combination, with a rotatable spindle, of centrifugally-acting bobbin-clutching members carried thereby, to engage and effect

rotation of a bobbin with the spindle, and means to retract said members when the spindle is running bare, the application of a bobbin to the spindle acting through said means to release automatically the clutching members and permit them to coöperate with the bobbin. 70

2. The combination, with a rotatable spindle, of centrifugally-acting bobbin-clutching members carried thereby, to engage and effect 75 rotation of a bobbin with the spindle, and spring-controlled means to coöperate with and normally retract said members, the application of a bobbin to the spindle acting through said means to release automatically the clutching members and permit them to coöperate with the bobbin. 80

3. The combination, with a rotatable spindle, of centrifugally-acting bobbin-clutching members carried thereby, to engage and effect 85 rotation of a bobbin with the spindle, a motion-limiting raceway for the upper ends of the clutching members, movable with relation to the spindle, and means to move said raceway in one direction to retract said members, the engagement of the bobbin with the raceway moving it oppositely to release and permit outward clutching movement of the said members. 90

4. The combination with a rotatable spindle having motion-limiting raceways, one of which is movable with relation to the spindle, and a spring to move said raceway in one direction, of centrifugally-acting bobbin-clutching members having their upper and lower 95 ends loosely held by said raceways, and means to retract the clutching members by or through spring-induced movement of the movable raceway, the application of a bobbin to the spindle moving it oppositely and permitting the 100 clutching members to expand. 105

5. The combination with a rotatable spindle having motion-limiting raceways, one of which is vertically movable on the spindle and provided with an annular cam, and a spring 110 to raise said raceway, of upright, centrifugally-acting bobbin-clutching members having their upper and lower ends loosely held in the raceways, the spring-induced movement of the movable raceway acting through the 115 cam to press inward the adjacent ends of the clutching members, the application of a bobbin depressing the movable raceway and thereby causing the cam to release the clutching members and permit them to expand. 120

6. The combination with a rotatable spindle having a fixedly-attached seat, a vertically-movable collar on the spindle above it and provided with a cam, and a spring to lift the collar, of upright, centrifugally-acting clutching members supported loosely at their lower ends in the seat, the upper ends of said members being bent over and inward to coöperate with the cam, spring-induced movement of the collar causing the cam to act upon the upper ends 125 130

of and draw in the clutching members, the application of a bobbin to the spindle depressing the collar and its cam, to thereby permit outward clutching movement of the said members.

7. The combination, with a rotatable spindle, of centrifugally-acting bobbin-clutching members carried thereby, to engage and effect rotation of a bobbin with the spindle, means to coöperate with the upper ends of and govern the outward movement of said clutching members, and a spring acting upon said means to render said members inoperative, the application of a bobbin to the spindle acting upon said means in opposition to the spring, to permit outward clutching movement of the clutching members.
8. The combination with a rotatable spindle having motion-limiting raceways, one of which is vertically movable on the spindle and

provided with an annular cam, and a spring to raise said raceway, of upright, centrifugally-acting bobbin-clutching members having their upper and lower ends loosely held in the raceways, the spring-induced movement of the movable raceway acting through the cam to press inward the adjacent ends of the clutching members, the application of a bobbin depressing the movable raceway and thereby causing the cam to release the clutching members and permit them to expand, and stops fixedly secured to the spindle to limit the vertical movement of the movable raceway.

In testimony whereof I have signed my name to this specification in the presence of two subscribing witnesses.

ANDREW D. MORSE.
